Whirlpool 27' Front Load Washer and Electric Dryer posted by Goemans Appliances posted date Nov. 13, 2017, © YouTube, [online], [site visited Nov. 3, 2019]. Available from Internet, <https://www.youtube.com/watch?v=Pq9GhOMLHPk> (Year: 2017).

Primary Examiner — Michelle E. Wilson*Assistant Examiner* — Richard E Yenchesky(74) *Attorney, Agent, or Firm* — McGarry Bair PC**CLAIM**

The ornamental design for a laundry treating appliance, as shown and described.

DESCRIPTION

FIG. 1 is a top perspective view of a laundry treating appliance, showing my new design;

FIG. 2 is a top view thereof;

FIG. 3 is a front view thereof;

FIG. 4 is a left side view thereof; and,

FIG. 5 is right side view thereof.

Portions of the drawings shown in broken lines form no part of the claimed design.
